DISPLAY PACKAGE KIT

Herbert J. Stern, New Rochelle, N. Y., assignor to
I. Stern & Co., Inc., New York, N. Y., a corporation of New York

Application September 17, 1949, Serial No. 116,369

2 Claims. (Cl. 206—45.11)

1

This invention relates to a display package kit useful in handling the distribution and sale of merchandise such as dental gold wire to the trade.

In the manufacture and sale of precious metal wire, such as gold wire largely used in connection with dental restoration work (for clasps, stress breakers, and other denture parts), there exists a need for convenient handling means in respect to packaging, shipping, storing, displaying, identifying and computing the prices of given lengths of wire. For example, one make of gold wire is sold in one-foot straight lengths, and the present invention proposes a simple solution for the several handling operations involved in merchandising it.

The conventional method or current technique involved in filling an order for gold wire is to use a micrometer for checking the sizes and cross sectional shapes of wires, taken from a particular stock lot, as called for by the order being filled. The particular set of wires finally selected as being correct for the order is then weighed. The weight of the selected set of wires is then multiplied by its unit price to obtain the total price. This procedure is repeated for such other sets of wire types from separate stock lots as may be required by the order. Thereupon, the several products of the several selected sets of wires are added in order to arrive at an invoice total.

The foregoing conventional procedure in filling a gold wire order is time consuming, clumsy and introduces the possibility of error, particularly over the sales counter where there is need for promptness and accuracy in behalf of a waiting customer. It is a problem not yet solved by the prior art for the benefit of this particular field.

This invention solves the foregoing distribution and sales problems by supplying the trade with a display case or kit containing individually packaged one-foot gold wire lengths in pre-computed assorted sizes and shapes. Each package is printed with the essential factors involved in its sale, particularly with a legend identifying the gold alloy formula, as well as the unit price and the total price of the wire piece in each particular package. At the sales counter, the several packages in the kit selected by a customer are pulled from the kit and placed vertically one overlapping the other. This lines up in columnar form the several printed total prices (irrespective of differences in unit price) and provides for a quick addition to obtain a total

2

invoice amount of the several packages pulled from the kit for sale.

Accordingly, this display kit with its dental gold wire stock is convenient for use by salesmen and on store counters; it aids in the selection of proper size wires which dentists or dental laboratories may desire to purchase in individual pieces or assorted lots and provides convenient storage means for a stock of gold wires. Of importance is the fact that this display kit makes it possible to tell at a glance (take inventory) what is the weight and value of the precious metal wire stock left on hand after a sale and thus facilitates the re-ordering of particular wire sizes and shapes by which to maintain a full kit supply.

Accordingly, in implementing the foregoing improvements for the distribution and sale of dental wire, it is a purpose of this invention to provide display packages—each of which contains a piece of wire—which stack together in an orderly lot within a housing or casing, with such an arrangement in the new combination of packages and casing to provide a kit that the identity of each wire is shown in the stack, that any one or more of the wire packages may be withdrawn from the stack for inspection and sale without disarranging the other packages in the kit, and that replacement packages of the wire may be inserted readily without disturbing the orderly arrangement of separate packages in said stack.

One satisfactory structural example, chosen for disclosing the invention herein comprises a display card printed on its upper margin with legends descriptive of the particular wire piece contained within a tubular compartment or receptacle formed integrally along the lower edge of the card, a supply of these compartmented display cards being arranged in combination and also carried with a handy storage casing of foldable form holding a supply lot of separate packages in orderly display and pre-computed price arrangement in kit form. The present example of the invention has proven to be a safe, accurate and convenient means for handling stocks of gold wires at the factory and in dental supply stores.

The drawings

The accompanying drawings with description and claims explain the invention as preferred and embodied at this time for an understanding of the problems sought to be solved. Since the teachings herein may suggest structural changes to others who wish to avail themselves

of the benefits of the invention, it is pointed out that subsequent modifications hereof may well be the same in spirit and principle as this disclosure.

Sheet 1 of the original Patent Office drawings shows the kit of wire packages somewhat smaller than actual commercial size used for one-foot wire lengths. On the other hand, Figs. 4 and 5 illustrate the package per se in actual size. And the remainder of the views are enlarged in order to bring out details not shown in the first five views.

Fig. 1 shows the storage function of the wire kit. It is folded into closed position, book-like in function, the individual packages of assorted wires being concealed from view.

Fig. 2 shows the display function of the wire kit. It is unfolded into open position, revealing the supply of wire packages stacked in place on each pivoted half portion or panel of casing of the foldable kit. Elastic bands embrace and snugly hold the stacked wire packages releasably in place for convenient withdrawal and replacement.

Fig. 3 is a fragmentary end elevation of several wire packages nested in stacked arrangement on the inside flat surface of one of the foldable kit panels, the elastic band (shown in Fig. 2) being omitted for clarity in order to observe the display card portions of the packages standing outwardly from the compartment portions thereof. This view may be regarded as an end elevation of Fig. 2, just four of the wire packages being shown as a sufficient number to demonstrate how the compartmented cards stack one on and against the other in a tier within the kit of Figs. 1 and 2.

Fig. 4 shows the front side or face view of one of the wire packages withdrawn from the storage display kit, being the side having printed legends specifying the type, size, shape, weight and price computation of the wire piece in the package.

Fig. 5 shows the rear side or back view of the wire package. This side may be printed with instructions and other data concerning the wire, manufacturer's name, etc., these being omitted from the drawing for the sake of clarity.

Fig. 6 is a transverse section through the pack-on the line 6, while Fig. 7 is a transverse section on the line 7 through a front side view opening or window of the package, and Fig. 8 is a transverse section on the line 8 through a rear side view opening or window.

Fig. 9 shows an enlarged fragmentary detail of one of the wire packages. This is an end view in perspective, showing the closure flaps of the wire compartment in open position, with a stiffening form or reinforcing channel in the tubular compartment to maintain its shape. One end of a piece of dental wire is seen ready to be withdrawn for use by a dental mechanic, whereupon the empty package is discarded.

Fig. 10 is a perspective view of a fragment of the forming or stiffening channel comprising a transparent plastic insert for the lengthwise compartment and acting not only to prevent the collapse and flattening of the long tubular compartment but also to impart stiffness to the long strip-like display card made integrally with the compartment.

The package

In describing the invention in greater detail, reference is first made to the construction of the package per se. It consists of a rectangular card-

board strip in the form of an elongated display card 2 having a wire container in the form of an elongated tubular compartment 3. The display card 2 has lengthwise parallel straight upper and lower edges, and the tubular compartment 3 is formed along the extreme lower edge of the display card.

In the present example of the package, its card portion 2 provides space on both sides for sales data or legends in the form of printed matter, while its container portion 3 receives a wire W (usually a one-foot straight length) alloyed from precious metal, as well as sized and shaped in cross section, to fill the needs of dentists, dental mechanics and laboratories in the production of denture restorations. The package is made of cardboard or hard paper stock and is discarded after the wire W is removed for use.

One or more closure flaps 4 of conventional type are provided at each end of the wire compartment 3 for opening and closing it. Two front side view openings, in the form of apertures or windows 5, may be provided through the front of the tubular compartment 3. Another view opening, also in the form of a window 6, may be provided through the rear of the compartment 3. These view openings 5 and 6 are illustrative, may be made to advantage in the positions shown, or otherwise placed, or varied in number, for the purpose of observing that the package portion 3 contains the wire W and in some instances several wires, if it is desired that they be packed in multiple.

The long tubular wire receptacle or compartment 3 is shown as being square in cross section, and this form thereof provides a flat stacking ledge or shoulder 7 in the nature of a supporting step along the entire length of the upper surface of the compartment at the rear side of the display card strip 2. Inasmuch as the package is manufactured of paper stock, it follows that its tubular compartment 3 may flatten or collapse due to handling, thus losing the function of the flat length stacking shoulder 7 set at right angles to the plane of the display card 2.

In accordance with one principle of the invention, it is desirable to maintain the original shape of the tubular compartment 3 in order that a large number of wire display packages may be stacked together in tiers and in parallel arrangement, as in Figs. 2 and 3. The flat ledge 7, as a rest or a stacking ledge, is thus important. Accordingly, an insert 8 is made in the form of a channel or trough, that is U-shaped in cross section, and of a length approximating the wire piece W.

The elongated stiffener or reinforcement member 8, adapted as a form for the compartment 3, is shown in perspective in Fig. 10. It is preferably made of transparent plastic and is slid into one end of the tubular compartment 3 to form and maintain the original straight-line and tubular shape thereof, here shown as being square or rectangular in cross section, thus making the stacking ledge 7 positive or permanent. Actually, it may be advisable to make the compartmented display cards 2 and 3 slightly longer than the one-foot measure of the gold wire W and the stiffener channel 8 (see left end of Fig. 5), in order that the closure flaps 4 may readily tuck into the tubular compartment ends to close them without interference with the end of the channel member. However, the plastic stiffening channel 8 has an easy fit in the wire tube 3,

and the thin edge of the flaps 4 readily push into place, as will be understood by observing Fig. 9.

The web of the transparent plastic stiffener 8 extends across the view openings, say the front ones 5, and the parallel flanges of the stiffener channel are contiguous to the upper wall (the stacking shoulder ledge 7) and lower wall of the wire compartment 3. Thus the wire W is readily observed through the plastic windows 5 provided on the front side of the compartmented display card package. It is now understood how the stiffener strip or channel 8 gives body and strength to the package as a whole, by maintaining the shape of the wire compartment 3 and the card 2 in straight and flat form.

As an example of one character of legend which may be printed on the upper margin of the display card 2, reference is made to Fig. 4. It is seen that the first legend P-33 may be printed on the display card as a legend or symbol to indicate the gold alloy formulation and constituency of the wire W contained in that particular package 2. Next, the legend 17-RD gauge may be employed to designate that the particular wire size is 17 gauge and round in cross section. Then note that it weighs 2.40 dwt. (penny weight) and that the unit cost is shown to be at the rate of \$1.75 per dwt. The product of the weight and unit rate gives a total amount as shown by the legend AMT. \$4.20 for the wire in the package. This is exemplary of one satisfactory plan employed for the purpose of price marking (pre-computing) the cost of the gold wire.

By observing Fig. 2, it will be understood that a supply of assorted wires W comprises a considerable number of individual packages, and that they may contain a different gold alloy formulation, as well as different weights of wire, also different cross section shapes and sizes. Printed descriptions for all these different characteristics (as well as the pre-computed prices) are on the margin of the card and parallel to its upper straight edge. An example of this layout is given in the foregoing description and shown in Fig. 4 of the drawings.

The structural features and legend markings of the package have been described for the purpose of enabling a manufacturer to carry out the foregoing package preparation, and thus make it convenient for the supply stores, laboratories and dentists in general, to make their purchases and re-orders in accordance with the printed legends on the wire packages.

The foregoing describes the structure and utility of an individual wire package comprising its display card 2 and tubular compartment 3 which is adapted to receive and hold the wire piece W. By reference to Fig. 2, it is seen that a large number of these packages—containing assorted wire shapes and sizes as well as different values—are used by the manufacturer in making up a complete dental wire display kit comprising the casing shown in Figs. 1 and 2 with the package shown on sheet 2.

Incidentally, the single wire W shown in the drawings is a round wire, and only one size is illustrated, but it is representative of the different cross sectional shapes as well as various sizes used by the trade. This point and others will be more fully appreciated as the description continues, especially in reference to the kit as a whole comprising a plurality of the card packages 2 carried in the casing.

Second The casing and package combination.

A housing or casing 10 is provided in the exemplary form shown on sheet 1 of the drawings and with the card-like packages 2, as well as other fittings next described, constitutes the gold wire assortment kit in the novel combination herein disclosed and distinguished from the prior art.

The casing comprises a set of panel flaps 10 (for example, two panels) pivoted on each other, and this part number also indicates the casing in general. The panels are shown as being of equal size and made of flat thin sheet material usually covered by a fabric. Either or both panels 10 constitutes a support for a number of the wire packages, and the two panels have a book-like function in their opening and closing action.

A backbone piece, in the form of an elongated hinge plate 12, serves to join the two panels 10 in relatively foldable relation. The conventional fabric covering envelopes the two panels 10 and also the hinge plate 12, thus providing a neat overall housing finish. The pliable fabric covering also constitutes a hinge or folding means where the two panels 10 join the parallel edges of the hinge plate 12.

One end flange 13 is provided in any suitable manner at the end of one panel 10, thereby leaving open the other end and the front side of that panel. For example, the panel 10 having the single end flange 13 happens to be the panel standing in upright position in Fig. 2. The other panel 10 is provided with a similar end flange 14 but at the end of the casing which is opposite the first flange 13. Thus the two panels 10 have oppositely disposed end flanges 13 and 14 so placed that when at closed positions (Fig. 1), both ends of the casing are shut by its two end flanges and thus securely retain the stack of wire packages 2 in place.

Further, one of the panels 10 is made with a front edge flange 15, one end of which may join with the end flange 14 on that panel. Thus one of the panels 10 has two flanges 14 and 15, the other an end flange 13, and all together the three flanges on two panels provide a complete enclosure at both ends and at the front edge of the closed casing 10. The depths of the three flanges and of the hinge plate 12 are all equal, in order that the two book-like panels (when closed) lie parallel with each other.

Next, it is observed (Fig. 2) that a pair of elastic bands 16 is provided on the inner surface of each panel 10, the casing as a whole being equipped with four elastic bands arranged in pairs. These resilient tensioning bands 16 are disposed on and transversely to the lengthwise axis of the foldable panels and packages 2 carried thereon. Each band end is folded back upon itself in semi-loop manner and is permanently fastened in any suitable way to the inner surface of the panel.

Accordingly, the cross runs of the bands 16 are elastically free and convenient for manipulation in their tensioning and light compressive action across the stack of packages 2. The respective pairs of resilient bands snugly embrace the tiers of packages stacked shoulder to shoulder (the ledge 7) and hold them in orderly parallel relation.

The elastic bands 16, while maintaining the packages 2 in stacked form, at the same time afford sufficient give or relaxation of tension as to enable one to readily use his fingers to stretch one or more bands, thereby easing the band com-

pression and making it convenient to withdraw one or more packages from the stack or replace them therein. It is seen that the extremities of the packages abut and stop against the casing end flanges 13 and 14 at opposite ends of the panels 10. Hence the packages of the two respective panels are withdrawn and replacement packages inserted in oppositely moving directions and also in a direction parallel with the front side flange 15 without disturbing the other packages in the stack.

According to the foregoing—especially the description in the previous topic concerning the marking legends on Fig. 4—it is now clear that any number of wire packages 2 may be withdrawn from the casing 10 of the wire kit and placed in alignment one above the other. In other words, the salesman lines up in columnar form the several amounts (one being \$4.20 in Fig. 4) and thereupon makes a total of the several pre-computed prices of the different characteristic gold wires.

It is believed clear how the invention serves to expedite transactions involving any number of gold wires selected package by package by a customer, where the wire characteristics, the gold content, the pennyweight, etc. (hence the price) may vary to a considerable extent.

This disclosure explains the principles of the invention and the best mode contemplated in applying such principles, so as to distinguish the invention from others; and there is particularly pointed out and distinctly claimed the part, improvement or combination, which constitutes the invention or discovery, as understood by a comparison thereof with the prior art.

This invention is presented to fill a need for a new and useful display package kit. Various modifications in construction, mode of operations, use and method, may and often do occur to others, especially so after acquaintance with an invention. Accordingly, it is to be understood that this disclosure is exemplary of the principles herein and embraces equivalent constructions.

What is claimed is:

1. A display package kit comprising, in combination, a casing having a pair of foldable panels, pivoted on a hinge plate, which open and close onto each other to provide a said casing of flat form; and a plurality of elongated packages, each one having a sales-data card defined by upper and lower lengthwise parallel edges, with a tubular compartment on and along the lower lengthwise edge of each card and adapted to hold merchandise for sale; the elongated packages being horizontally stacked within the casing, on each panel thereof, and hence on display when

the kit is open, the tubular compartments resting against each other and forming a said stack of packages on each panel, with the sales-data cards partially overlapping one another, but the upper margin of each said card being exposed to view; and a tensioning band means mounted on each panel, transversely of the elongated packages, embracing and holding them in each said stack; and a flange on one end of each panel, at opposite ends thereof, said flanges being disposed transversely of the length of the packages and having a depth at least as great as the combined thickness of the two stacks, said flanges covering both ends of the casing and hence both ends of the stacks when said casing is closed, but exposing one end of each panel and hence one end of each stack when said casing is open, by which any one or more packages may be withdrawn from each stack out through the exposed end thereof without disturbing the other packages in said stacks.

2. A display package kit as defined in claim 1, but having a third flange on the front side of one of the panels, by which said three flanges enclose both ends as well as the front side of the flat casing when said two panels are folded into closed position, and by which the opposite ends of the two panels are open when the casing is in open position; and thereby adapting one or more of the elongated packages stacked on either panel, when the casing is open, to be withdrawn from or replaced in its stack, by movement along one direction from one panel and along an opposite direction from the other panel, both movements being parallel to the third flange, and thus withdrawn from or replaced within the embrace of the tensioning band means without disturbing the other packages in said stack.
